F. P. SHEK.
CAN OPENER.
APPLICATION FILED MAY 17, 1921.

Patented Aug. 15, 1922.

UNITED STATES PATENT OFFICE.

FRANK P. SHEK, OF BROOKLYN, NEW YORK.

CAN OPENER.

1,425,704.

Specification of Letters Patent. Patented Aug. 15, 1922.

Application filed May 17, 1921. Serial No. 470,351.

To all whom it may concern:

Be it known that I, FRANK P. SHEK, a citizen of the United States, residing in Brooklyn, in the county of Kings, city of New York, and State of New York, have invented certain new and useful improvements in Can Openers, of which the following is a full, clear, and exact specification.

My invention relates to can openers and 10 refers particularly to can openers capable of producing openings having smooth edges at the outer periphery of a can top.

It is frequently desirable to make openings in a can top which will allow the ready 15 and complete removal of the contents by flowing the contents therethrough.

It is likewise frequently desirable to open 20 a can by the partial, or complete removal of the top from the sides thereof with the formation of smooth edges at the line of separation.

The device of my invention accomplishes 25 these, and other desirable results in an easy manner, is cheap of construction and positive in results.

Condensed milk, and other similar liquids, are usually removed from the can by making two small openings therein, one for the admission of air and the other for the flow 30 of the liquid.

It is evident that if the liquid opening be some distance from the periphery of the top, all of the liquid can not be poured from the can by the simple tilting thereof, but the 35 latter portions thereof can be removed only by a shaking process.

It is also evident that the inwardly pressed edges of the top around the opening will act as a flange and prevent the removal of all the liquid by a flowing movement thereof.

The device of my invention overcomes 45 both of these difficulties, as by its employment the opening is made at the extreme periphery of the top and the impressed metal is forced flush with the side of the can, thus offering no impediment to the outward flow of the entire contents when the can is tilted.

Further, when a series of connected openings are made by my device around the 50 outer periphery of the top, the line of separation forms a smooth edge around both the side of the can and the top of the can.

The device of my invention, therefore, 55 presents an effective and practical means for

opening a can with the production of desirable and valuable results.

In the accompanying drawings, illustrating modified forms of the device of my invention, similar parts are designated by 60 similar numerals:

Figure 1 is a perspective view of one form of my device, showing its application to a can.

Figure 2 is a section through the line 65 2-2 of Figure 3.

Figure 3 is a top plan view of the device in the direction of the arrow of Figure 1.

Figure 4 is a side plan view of a modified 70 form of my punching device.

Figure 5 is an end elevation of Figure 4.

Figure 6 is a sectional view showing the opening formed by the device of Figures 1, 2 and 3.

Figure 7 is a top plan view of the punching 75 device Figures 4 and 5.

The particular form of the device of my invention, shown in the accompanying drawings, comprises a guide having a sector portion 10, capable of placement around 80 the can 11 and a top member 12. Fixedly attached to the upper face of the guide member 12, by the rivets 13, 13, is a resilient arm 14. Movable attached to the other extremity of the arm 14, by the screws 15, 15, 85 is a wooden handle 16, the screws passing through the slots 24, 24 of the arm 14. Passing through a slot 23, within the arm 14, is a punch 17, which is fixedly attached to the handle 16 by the extended portion 18, which 90 is driven into the under portion of the handle. The outer face of the punch 17 is flat, or slightly circular, and the inner face is circular in the form of punch, shown in the accompanying drawings.

The handle 16 and the punch 17 can be moved longitudinally along the arm 14, by loosing the screws 15, 15, sliding them along the slots 24, 24 and then screwing them in tightly when the punch 17 is in the proper 100 position.

The operation of the device is as follows:

The guide is placed against the side and top of a can and, while held in that position, punch 17 is fixed in proper position and the 105 handle 16 is pressed firmly downwardly, as shown in dotted lines of Figure 4, the punch entering the can top 19 forming an opening therein. The position of the punch 17, with respect to the guide 10, is such that 110

the outer face of the punch 17 will practically abut upon the outer edge of the can top 19, when the punch is pressed therethrough. This operation forms an opening in the can top 19, as shown in Figure 6. The portion of the can top 19 around the outer edge of the opening, will be forced downwardly, as at 20, against the inner face of the can side 10. It will thus be seen that the opening 10 will be formed at the extreme extremity of the can top and that the cut portion will be pressed against the side of the can, hence, there is nothing to prevent the entire contents of the can from flowing through the 15 opening when the can is placed in an inclined position. A similar opening is made in another portion of the can top to admit air.

In the modification shown in Figures 4, 5 20 and 7, a punch 21 is attached to the under face of the plate 26, by means of the rivets 22, 22, passing through the angular member 25 of the punch 21. The plate 26 is fixedly attached to the handle 16 by means of the 25 screws 27, 27, 27, which pass through the slots 28, 28, 28 in the arm 14, thus allowing of the positioning of the punch 21 along the arm 14. The punch 21 is triangular in shape, the outer face of which is convex to 30 correspond with the circular shape of a can.

The operation of this modified form of my device is as follows:

The guide and punch are placed, as described above, and the handle 16 pressed 35 downwardly, this producing an elongated opening, or slot, along the outer periphery of the can top. The guide is then moved slightly and the operation repeated, the opening thus formed producing an elongated opening connecting with the first 40 opening. By repeating this operation, a portion, or the entire, of the top may be cut

away from the side of the can. The operation separates the top from the side at practically their line of jointure, a portion of 45 the top being pressed downwardly and outwardly against the inner face of the can, thus forming a smooth edge.

It is evident that other guide means may be employed and that the handle need not 50 be resilient.

I do not limit myself to the particular size, shape, number or arrangement of parts, as shown and described, all of which may be varied without going beyond the scope of 55 my invention as shown, described and claimed.

What I claim is:

1. In a can opener, in combination, a segmental guide capable of placement around 60 a portion of the edge of a can, a resilient arm fixedly attached to the guide, a downwardly extended punch carried by the arm and a knob carried by the arm above the punch.

2. In a can opener, in combination, a segmental guide capable of placement around a portion of the edge of a can, a resilient arm fixedly attached to the guide, a knob carried by the arm and a downwardly 70 extended punch carried by the knob.

3. In a can opener, in combination, a segmental guide capable of placement around a portion of the edge of a can, a resilient arm fixedly attached to the guide, a knob carried by the arm, a downwardly extended punch carried by the knob and means for positioning the arm and punch at predetermined positions along the arm.

Signed at New York city in the county of 75 New York and State of New York this 16th day of May, 1921.

FRANK P. SHEK.
